JOHN E. CANNADAY AND HARRY BENTON CANNADAY, OF ANDER-
SON, AND HATTIE V. BRAGG, OF RICHMOND, INDIANA.

DRAW-BAR FOR RAILWAY-CARS.

SPECIFICATION forming part of Letters Patent No. 614,769, dated November 22, 1898.

Application filed August 31, 1897. Serial No. 650,194. (No model.)

To all whom it may concern:

Be it known that I, SAMUEL E. SECOY, a citizen of the United States, and a resident of Marion, in the county of Marion and State of Ohio, have invented certain new and useful Improvements in Draw-Bars for Railway-Cars; and I do hereby declare that the following is a full, clear, and exact description of the invention, which will enable others skilled 5 in the art to which it appertains to make and use the same, reference being had to the accompanying drawings, which form a part of this specification.

My invention relates to safety devices for 15 the draw-bars of automatic car-couplers; and its object is to provide improved means whereby should the draw-bar become unfastened from the car the cars will be automatically uncoupled and the draw-bar also be prevented 20 from falling onto the track.

The invention consists in the novel construction and combination of parts hereinafter fully described and claimed.

In the accompanying drawings, Figure 1 is a plan view showing a draw-bar constructed 25 in accordance with my invention. Fig. 2 is a longitudinal section of the same, showing the parts in position when in use, the dotted lines showing how the lock is elevated to allow 30 the jaws to be coupled and uncoupled. Fig. 3 is a similar view showing the position the parts would assume should the draw-bar be unfastened from the car. Fig. 4 is a side view of the locking-bar. Fig. 5 is a bottom 35 view of the same.

In the said drawings the reference- 40 numeral 1 designates a hollow or chambered draw-bar rectangular in cross-section and formed at the front or outer end with jaws 2, to one of which is pivoted the knuckle of 45 the coupler and the other of which is engaged by the pivoted knuckle of an adjoining car. In rear of these jaws is a vertical pin 3, passing through a hole in the upper side of the draw-bar. The lower end of this pin is provided with an extension 4, formed with a slot 5. Working in this slot is a pin 6, carried by an arm 7 on the front or outer end of a locking-bar 8. This bar has its front end bevelled, as seen at 9, and is designed to engage

with the point of the knuckle of the coupler and hold the knuckles securely coupled together until said bar is removed from engagement with said point. The rear end of this bar is formed with rounded head 10, which 55 works in a curved socket 12 in a block 13, forming a ball-and-socket joint. This block is formed on opposite sides with pins 14, which work in inclined slots 15 in the sides of the draw-bar. Connected with these pins, which 60 project beyond the sides of the draw-bar, are chains 16, the other ends of which are secured to the car. When the draw-bar is in use or proper working condition, these chains are slack, as seen in Fig. 2. Formed on the under side of said block are rounded or curved 65 lugs or ribs 17, which when the parts are in the position shown in Fig. 2 seat in a recess 18 in the bottom of the draw-bar. These lugs are formed with holes 19, through which and 70 corresponding holes in the draw-bar passes a key or pin 20. This key is simply to hold the block in place under ordinary circumstances and will break in case the draw-bar becomes unfastened, as hereinafter described. 75

The operation is as follows: As the cars approach each other the pin 3 is elevated, so as raise the locking-bar 8 to allow the knuckles to couple. The pin and bar are then allowed to drop, so that the beveled end of the bar 80 will engage with the point of the knuckle, and thus hold the knuckles securely coupled together. The parts will now assume the position shown in full lines, Fig. 2.

In case the draw-bar should become unfastened from the car it will be pulled forward until the slack of chains 16 is taken up, when the latter will pull upon the block, breaking the key 20 and drawing the block back, as seen in Fig. 3, and also drawing the locking-bar away from the knuckle, so that the latter will swing out and cut the train apart. The draw-bar will also be prevented from falling onto the track by means of the chain. The purpose of the slotted extension 4 of pin 3 is to prevent injury of the pin when the locking-bar is drawn back, the pin of said bar working in the slot.

From the above it will be seen that accidents from the draw-bars becoming unfas- 100

tened and falling on the track, as is now frequently the case, is entirely obviated, as the car will be automatically uncoupled should the draw-bar become unfastened, and the latter is also prevented from falling upon the track.

Having thus fully described my invention, what I claim is—

1. The combination with the chambered draw-bar, having an inclined slot in its sides, of the slideable block provided with pins projecting through said slots, the chains connected with said block, the locking-bar pivotally connected with said block and means for elevating said locking-bar, substantially as described.

2. The combination with the chambered draw-bar, having inclined slots in its sides and a curved recess in its bottom, of the slideable block, the pins secured thereto projecting through said slots, the chains connected therewith, the rounded lug or rib on the under side of said block engaging with the said recess in the draw-bar, the locking-bar pivotally connected with said block and means for elevating the same, substantially as described.

3. The combination with the chambered draw-bar, having inclined slots in its sides, and a curved recess in its bottom, of the slideable block, the pins secured thereto projecting through said slots, the chains connected

therewith, the rounded lug or rib on the under side of said block seated in said recess, the key passing through said lug and through the sides of the said recess, the locking-bar pivotally connected with said block and means for elevating the same, substantially as described.

4. The combination with the chambered draw-bar, the slideable block, the pivoted locking-bar, the arm secured thereto and the pin secured to said arm, of the elevating-pin provided with an extension formed with a slot with which the pin on said arm engages, substantially as described.

5. The combination with the chambered draw-bar, having inclined slots in its sides and a rounded recess in its bottom, of the slideable block, the pins and chains connected therewith, the rounded lug on said block, the key, the locking-bar connected with said block by a ball-and-socket joint, the arm at the front end of said bar, the pin secured thereto and the elevating-pin having a slotted extension, substantially as described.

In testimony that I claim the foregoing as my own I have hereunto affixed my signature in presence of two witnesses.

SAMUEL E. SECOY.
